REGULATOR FOR PRESSURIZED FLUID

Clair Dean Holben, Denver, Colo., assignor to
C. A. Norgren Co., Littleton, Colo.

Filed Oct. 4, 1973, Ser. No. 403,547

Term of patent 14 years

Int. Cl. D23—01

U.S. Cl. D23—21

FIG. 1 is a perspective view of a regulator for pressurized fluid showing my new design;

FIG. 2 is a top view thereof;

FIG. 3 is a side elevational view thereof;

FIG. 4 is a bottom view thereof; and

FIGS. 5, 6 and 7 are additional side elevational views thereof.

I claim:

The ornamental design for a regulator for pressurized fluid, as shown.
